[57] CLAIM

The original design for a dish, as shown.

DESCRIPTION

FIG. 1 is a top view of a dish showing my new design; FIG. 2 is a bottom view of the dish;

FIG. 3 is a side view of the dish (symmetrical around the dish); and

FIG. 4 is a fragmentary cross-sectional view taken along line 4—4 of FIG. 1 on an enlarged scale.

FIG. 4

FIG. 2

FIG. 3
